UNITED STATES PATENT OFFICE.

JAMES K. McCATHRAN, OF WASHINGTON, DISTRICT OF COLUMBIA,
ASSIGNOR TO ELLIOTT-FISHER COMPANY, OF NEW YORK, N. Y.,
A CORPORATION OF DELAWARE.

TYPE-WRITING MACHINE.

No. 838,045.

Specification of Letters Patent. Patented Dec. 11, 1906.

Application filed August 9, 1905. Serial No. 273,392.

To all whom it may concern:

Be it known that I, JAMES K. McCATHEAN, a citizen of the United States, residing at Washington, in the District of Columbia, have invented a new and useful Type-Writing Machine, of which the following is a specification:

This invention relates to paper guiding and cutting mechanism for type-writing machines, the object being to provide an attachment especially adapted to facilitate the use of continuous paper webs in the production of either single or manifold records, and having its parts capable of adjustment to accommodate webs of varying widths.

To the accomplishment of this object the preferred embodiment of the invention includes a paper-cutter extending lengthwise of and disposed adjacent to the platen and a pair of guides immediately associated with the cutter and relatively adjustable lengthwise thereof to position said guides at the opposite edges of the paper strip, no matter what the width of the latter may be.

In the accompanying drawings, Figure 1 is a front elevation of a type-writing machine equipped in accordance with my invention. Fig. 2 is a plan view thereof. Fig. 3 is a side elevation of so much of the machine as is necessary to show my invention. Fig. 4 is a sectional view showing the platen and associated parts on a somewhat enlarged scale. Fig. 5 is a detail view of the cutter-bar detached. Fig. 6 is a similar view of a bar of slightly-different form. Fig. 7 is a detail sectional view of a modified arrangement, the cutter-bar being carried by the paper-guide-supporting bar. Fig. 8 is a further modification involving the placing of additional pressure-rolls on the paper-guides; and Fig. 9 is a still further modification involving the idea of throwing the cutter-bar down to clamp the paper against the platen when the paper-guides are moved away from the platen.

Each part is designated by the same reference character throughout the drawings.

The type-writing machine is indicated as a whole by 1 and is or may be of ordinary form, involving a main frame 2, carrying key-operated printing mechanism and supporting a sliding truck or platen-carriage 3, supporting a cylindrical platen 4, which in the present instance is mounted in a platen-frame 5,

vertically movable upon the carriage 3 to facilitate the printing of upper and lower case characters.

Opposite the printing-point of the platen, which in the illustrated type of machine is at the front, are located two or more ribbon-sections *a* and *b*, alternating with two or more strips or webs of paper *c* and *d*, which are led under the platen and around the front side thereof from a suitable source of supply—as, for instance, a pair of paper-rolls *e* and *f*. It may be stated, however, that so far as my invention is concerned it matters not from what source the paper is led nor whether there are one or more webs, the invention being equally useful where a continuous web is provided for each of the several records in manifolding or where a single web is utilized for the copy and separate sheets for the original records. Similarly it is immaterial how the transfer of the type-impressions are effected, whether by a ribbon, as shown, or by the more usual method of interposing carbon-sheets.

Extending upwardly in rear of the platen from the frame 5 are two arms 6, constituting supports for a rock-bar 7, extending the entire length of the platen, Figs. 1 and 2, and of angular cross-sectional contour. Mounted on the rock-bar 7 to slide longitudinally thereof are a pair of forwardly-extending arms 8, to the front ends of which are attached a pair of paper-guides 9, in the form of leaf-springs longitudinally curved to conform to the contour of the platen and provided with pressure-rolls 10, which bear against the opposite margins of the paper strip and act as combined clamps and guides for the paper. The adjustment of the arms 8 along the bar 7 is designed to position the paper-guides with reference to paper strips or webs of different widths, it being possible to position these guides at any desired points within the length of the platen. When it is desired to draw the paper freely forward, the paper-guides are swung up, for which purpose the shaft 7 is mounted to rock, the guides being held in their elevated position by a spring 11, carried by one of the arms 6 (see Fig. 1) and bearing against the shaft 7. The arms 8 are retained in their adjusted positions by frictional engagement with the bar 7 or by any approved retaining means.

At this point it should be stated that the

structure thus far described was not invented by me and that I make no claim to any of the described parts, except as they may enter into new and useful combination with the part 5 per-cutter to be described.

As shown in Figs. 1 and 4, the angular front ends 12 of the arms 8, to which the paper-guides proper are attached, are extended upwardly to facilitate the adjustable attachment of an angular cutter-bar 13, extending the full length of the platen. This cutter-bar has its rear edge sharpened to form a knife or cutter, and it rests upon the arms 8 with the vertical wall or flange 14 of the bar 10 imposed against the rear sides of the angular ends 12 of the arms. The flange 14 of the cutter-bar 13 is provided with a pair of longitudinal slots 15 for the reception of headed clamping-screws 16, passed through the arm 15 ends 12 and provided in advance thereof with thumb-nuts 17. The screws 16 and nuts 17 constitute retaining devices connecting the paper-guides to the cutter-bar and permitting such guides to be adjusted along the bar and secured thereto in their adjusted positions. It is perhaps preferable to adjust both paper-guides along the knife, allowing the latter to remain relatively stationary. Obviously, however, it is possible to allow one of the 25 guides to remain relatively stationary while the other guide and the knife are moved lengthwise of the platen, or the knife and one of the guides may remain fixed while the other guide is moved to vary the distance between the two guides. In any case the paper-guides are relatively adjusted to accommodate a given width of paper, and the length of the cutting edge exposed between the guides is simultaneously adjusted to engage the full 30 width of the paper. By reason of this arrangement of the paper guides and cutter in a connected organization arranged to swing toward and from the platen it will be seen that when the guides are swung away from the 35 platen to facilitate the insertion of the paper or the free forward feed thereof the cutter is simultaneously moved and is restored again to its normal position when the guides or clamps are swung back to engage the web. As will be seen by reference to Fig. 4, the paper web or webs are led upwardly between the rock-bar 7 and the cutter-bar, and when it is desired to sever the paper it is simply necessary to draw it forward against the cutter in a 40 manner which will be obvious to those skilled in the art.

In Fig. 7 is shown a modified form of the invention, consisting in prolonging the paper-guides rearwardly and in securing the cutter-bar 13 rigidly to the rock-bar 7. In this case the guides and cutter-bar are both carried by a single rocking support—to wit, the bar 7—and obviously with this arrangement the cutter-bar may be formed integral with the bar 7, as shown in Fig. 8. This lat-

ter figure is marked by a further variation of the paper-guiding means, consisting in the provision of guiding and clamping rolls 10^a, mounted on the arms 8 in lieu of the rearward extension of the paper-guides, as shown in Fig. 7.

It will be noted that in those forms of the invention shown in Figs. 7 and 8 the paper guiding and cutting means, being located at opposite sides of the axis of the bar 7, are moved in opposite directions when the bar is rocked. In Fig. 9 I have shown a further form of the invention wherein I take advantage of this fact to cause the cutter-bar to be presented quite close to the platen, possibly 80 in clamping relation to the paper thereon, when the paper-guides are swung up to release the paper. This form is possessed of some advantages, for the reason that while the removal of the paper guides or clamps 85 permits the paper to be drawn forward with greater freedom the cutter-bar acts to clamp the paper with sufficient firmness to insure the proper cutting of the paper when the latter is drawn against the knife-edge. Furthermore, while the cutter-bar acts as a clamp during the cutting operation it is removed from the platen when the paper-guides are thrown down to their normal positions, and therefore does not interfere with 90 the normal feed of the paper during the writing operation.

In Fig. 6 is shown a modified form of cutter-bar which may be substituted for the bar 14 in that form of the invention illustrated in Fig. 4. The variation consists in providing the bar with a single slot 15^a instead of two slots 15, as in that form of bar shown in Fig. 5.

It is thought that from the foregoing the construction and operation of my attachment will be fully comprehended; but I wish it understood that I reserve the right to effect such changes, modifications, and variations of the illustrated structure as may come fairly within the scope of the protection prayed.

What I claim is—

1. In a type-writing machine, the combination with a platen, of a cutter-bar extending longitudinally of the platen and having its cutting edge located at that side of the bar which is farthest from the printing-line, and a pair of margin-guides extending toward the printing-line of the type-writer from the cutter-bar, said margin-guides being relatively adjustable independently of the cutter-bar to accommodate sheets of different widths and movable in unison toward or from the platen to clamp or release the sheet.

2. In a type-writing machine, the combination with a platen and platen-carriage, of a cutter-bar extending longitudinally of the platen and having its cutting edge located at that side of the bar which is farthest from the

printing-line, a pair of margin-guides located between the cutter-bar and the printing-line and relatively adjustable lengthwise of the platen to accommodate sheets of different widths, and a support sustaining the cutter-bar and margin-guides in a single organization and movable to withdraw the margin-guides from the platen or to present said guides thereto.

16. 3. In a type-writing machine, the combination with a platen and a cutter-bar disposed lengthwise thereof, of a pair of paper-guides connected to the cutter-bar and relatively adjustable longitudinally thereof.

15. 4. In a type-writing machine, the combination with a platen, of a rocking support, and paper-guides and a paper-cutter mounted on the support to rock therewith, the guides and cutter being oppositely disposed 20 with reference to the axis of the support.

5. In a type-writing machine, the combination with a platen, of a rock-shaft, and a pair of relatively adjustable paper-guides and a paper-cutter carried by the rock-shaft.

25. 6. In a type-writing machine, the combination with a platen, of a rock-shaft, a pair of forwardly-extending paper-guides carried by the rock-shaft, and a paper-cutter disposed in rear of the guides.

30. 7. In a type-writing machine, the combination with a platen, of a rock-shaft extending longitudinally thereof, a separate cutter-bar extending from end to end of the platen and connected to the rock-shaft to move 35 therewith, and a pair of relatively adjustable paper-guides extending forwardly from the cutter-bar and having operative connection therewith.

8. In a type-writing machine, the combination with a platen-carriage, of a platen mounted on the carriage, a rock-shaft carried by the platen-carriage and extending longitudinally of the platen, and paper guiding and cutting means connected in a single organization and carried by the rock-shaft.

45. 9. In a type-writing machine, the combination with a platen, of a pair of parallel

paper-guides, and a paper-cutter, said guides and cutter being relatively adjustable to secure any desired interval between the guides 50 for the accommodation of different widths of paper and to adjust the length of the effective cutting edge.

10. The combination with a front-strike typeewriter, of a movable cutter-bar extending longitudinally of the platen above the printing-point and having its cutting edge disposed rearwardly, and a pair of relatively adjustable margin-guides having connection with the cutter-bar for movement therewith 60 and extended around the front side of the platen.

11. The combination with a typeewriter, of a paper guiding and cutting structure mounted to rock on an axis disposed longitudinally of the platen, said structure including paper cutting and guiding means located at the opposite sides of the axis upon which the structure rocks, whereby the cutting means will be moved toward the platen 70 when the guiding means is moved away from the same.

12. The combination with a typeewriter, of a rocking bar disposed longitudinally of the typeewriter platen and having a cutter in 75 rear of its axis, and a pair of margin-guides carried by said bar and extended forwardly, whereby the rocking of the bar will move the cutting and guiding means in opposite directions.

13. The combination with a typeewriter, of paper-guiding means, paper-cutting means, and means for simultaneously moving both the guiding and cutting means to withdraw one of said means from the platen and to 85 present the other of said means thereto.

In testimony that I claim the foregoing as my own I have hereto affixed my signature in the presence of two witnesses.

JAMES K. McCATHRAN.
